Primary Examiner — Kendra Leslie Hamilton*Assistant Examiner* — Amanda Christensen*(74) Attorney, Agent, or Firm* — BCF LLP(57) **CLAIM**

The ornamental design for a solar panel, as shown and described.

DESCRIPTION

FIG. 1 is a top plan view of a first embodiment of a solar panel, showing our new design; and,

FIG. 2 is a top plan view of a second embodiment of a solar panel, showing our new design.

The broken lines in the Figures depicting substantially-rectangular, individual solar cells on a top surface of the solar panel form no part of the claimed design. The vertical broken line clusters on the top surface of the solar panel depict unclaimed elements.
